CLAIM

The ornamental design for a component for a health condition monitoring system, as shown and described.

DESCRIPTION

FIG. 1 is an isometric view of an exemplary embodiment of the component for a health condition monitoring system; FIG. 2 is a top view thereof;

FIG. 3 is a bottom view thereof;

FIG. 4 is a left side view thereof;

FIG. 5 is a right side view thereof;

FIG. 6 is a front view thereof; and,

FIG. 7 is a rear view thereof.

The portions of the component for a health condition monitoring system shown in broken line in FIG. 3 form no part of the claimed design.

1 Claim, 3 Drawing Sheets(56)
